United States Patent Office

Des. 204,796
Patented May 17, 1966

204,796

LAMP OR SIMILAR ARTICLE

Stanley D. Harrison, Los Angeles, and Maxey A. Hankins,
Encino, Calif., assignors to Mole-Richardson Co., Hol-
lywood, Calif., a corporation of California

Filed Apr. 26, 1965, Ser. No. 84,949

Term of patent 14 years

(Cl. D48—20)

FIG. 1.

FIG. 2.

FIG. 3.

FIG. 4.

FIG. 5.

FIG. 6.

FIG. 7.

FIG. 8.

FIG. 9.

FIG. 10.

FIG. 11.

FIG. 12.

FIGURE 1 is a front perspective view of a lamp or similar article showing our new design;

FIGURE 2 is a front elevational view;

FIGURE 3 is a side elevational view;

FIGURE 4 is a top plan view;

FIGURE 5 is a bottom plan view;

FIGURE 6 is a rear elevational view;

FIGURE 7 is a front perspective view showing a second embodiment of our new design;

FIGURE 8 is a rear elevational view of the lamp or similar article shown in FIGURE 7;

FIGURE 9 is a front perspective view showing a third embodiment of our new design;

FIGURE 10 is a rear elevational view of the lamp or similar article shown in FIGURE 9;

FIGURE 11 is a front perspective view showing a fourth embodiment of our new design; and

FIGURE 12 is a rear elevational view of the lamp or similar article shown in FIGURE 11.

The mounting brackets and electrical cables shown in broken lines, are included for illustrative purposes only.

The sides opposite those shown in FIGURES 7, 9 and 11 are, respectively, mirror images thereof.

We claim:

The ornamental design for a lamp or similar article, as shown and described.
